Primary Examiner — April Rivas*(74) Attorney, Agent, or Firm* — Proskauer Rose LLP**CLAIM**

The ornamental design for a luggage, as shown and described.

DESCRIPTION

FIG. 1 is a front perspective view of a piece of luggage showing our new, original and ornamental design embodied therein, in accordance with the present invention; FIG. 2 is a rear perspective view of the piece of luggage of FIG. 1; FIG. 3 is an elevated front view of the piece of luggage of FIG. 1; FIG. 4 is an elevated rear view of the piece of luggage of FIG. 1; FIG. 5 is a top view of the piece of luggage of FIG. 1; FIG. 6 is a bottom view of the piece of luggage of FIG. 1; FIG. 7 is a first elevated side view of the piece of luggage of FIG. 1; and, FIG. 8 is a second elevated side view of the piece of luggage of FIG. 1.

Any dash-dash broken lines in the drawings, including any dash-dash broken line over a claimed surface, represent unclaimed portions of the piece of luggage and form no part of the claimed design.

1 Claim, 8 Drawing Sheets(56)
